DESIGN FOR A CARTON OPENER OR SIMILAR ARTICLE

Walter J. Guenther, Fort Madison, Iowa

Application April 13, 1944, Serial No. 113,235

Term of patent 14 years

(Cl. D22—2)

To all whom it may concern:

Be it known that I, Walter J. Guenther, a citizen of the United States, residing at Fort Madison, in the county of Lee and State of Iowa, have invented a new, original, and ornamental Design for a Carton Opener or Similar Article, of which the following is a specification, reference being had to the accompanying drawing, forming part thereof.

Figure 1 is a top plan view of a carton opener or similar article, showing my new design;

I claim:

The ornamental design for a carton opener or similar article, as shown.

WALTER J. GUENTHER.
